POURING SPOUT

Lowell L. Smith, Rockford, Ill.

Application May 22, 1948, Serial No. 28,540

4 Claims. (Cl. 222—567)

1

This invention relates to spouts and more particularly to detachable spouts for pouring liquid from containers.

An object of the invention is to provide a spout of the above character with novel means for securing the spout to a container.

Another object of the invention is the provision in a spout of the above character whereby the spout may be secured to the container so that there is no leakage of liquid between the spout and the container.

Another object of the invention is the provision in a spout of the above character whereby the spout may be quickly attached to and removed from a container in a very easy manner.

Another object of the invention is to provide a spout of the above character that is sturdy, that is simple in construction, and that is relatively inexpensive to manufacture.

Other objects and advantages of the invention will become apparent from the following detailed description taken in connection with the accompanying drawings, in which—

Figure 1 is a perspective view of a spout embodying the present invention;

Fig. 2 is a sectional view taken along the longitudinal axis of the spout shown in Figure 1.

Fig. 3 is a front view of the spout in position on a container;

Fig. 4 is a sectional view similar to Fig. 3;

Fig. 5 is a perspective view of a modified form of the invention, and

Fig. 6 is a fragmentary exaggerated sectional view of a container similar to Fig. 4 with the spout of Fig. 5 in position.

Referring now to the drawings the invention is shown embodied in a detachable spout for facilitating pouring of liquid from a container. Although the spout disclosed herein may be used with various containers as will be apparent to those skilled in the art, it is shown for purposes of illustration as being used with a gable type container, utilized widely in the dairy industry in handling milk. To simplify the drawings, only those portions of the container necessary to understand the construction and operation of the spout are included. In general, such containers are formed from paper and include four interconnected side members of which only members 11 and 12 are shown and indicated. At their upper ends the side members are connected to inclined portions 13 and 14 respectively. The latter extend upwardly from the side members and are joined together intermediate the side members in a suitable conventional manner to

2

form a gable. The inclined portion 13 is formed with a flap 16, which in its closed position forms a part of the inclined portion and the upper end of the side member 11. The flap is defined by perforations so that by inserting one's fingernail or the like into a small slot 17 formed on the upper end of the side member 11 the flap may be torn up and raised to the position shown in Figs. 3 and 4 to uncover a pouring opening 18. The latter is formed in a liner 19, beneath and supporting the flap 16 when the latter is in its closed position, secured to the interior of the container. The liner extends from approximately the peak of the gable to a position below the connection between the side member 11 and the inclined portion 13. A tab 21 of the same size and shape as the opening 18 normally closes the opening 18 when the flap 16 is in the closed position. The tab 21 is adhered to the flap 16 in a suitable manner so that when the flap 16 is raised as shown the tab 21 is also raised to the position shown in Figs. 3 and 4.

The spout in general comprises a pad 22 having a flat surface 23 shaped to rest on the surface or land 24 adjacent and defining the opening 18. Attached to the pad 22 and projecting outwardly from the side thereof away from the flat surface is a liquid pouring or sleeve portion 26. The length of the latter and the cross-sectional shape thereof may vary as required. On an edge 27 the pad is abruptly beveled so that the edge may be forced under the tab 21 as shown in Fig. 4 to fixedly position the edge 27 of the pad 22 with respect to the container and force the pad down against the liner 19 and land 24. A resilient wedge member 28 is disposed on the opposite edge of the pad 22 and is inclined at an angle with respect to the flat surface 23 of the pad. In general this angle is slightly smaller than the corresponding angle between the inclined portion 13 and the side member 11. As best seen in Fig. 2, the resilient member is connected to the pad on the side thereof away from the flat surface 23 and in spaced relation thereto. A rib 29 connected between the sleeve portion 26 and the resilient member 28 may be utilized to strengthen the connection between the resilient member and the pad 22. The resilient member 28 tapers generally from its connection with the pad 22 to its free end 31. The latter is relatively thin so that it may be inserted between the liner 19 and the upper end of the side member 11 as shown in Fig. 4. The end 31 of the resilient member 28 may be curved slightly so that when the end is

inserted between the liner 19 and the side member 11, it is straightened out and is under stress. Thus, there is a tendency for the resilient member to be maintained in a fixed position with respect to the container. With some containers the end 31 may be straight since there is sufficient friction between the end and the side members to hold the resilient member in a fixed position with respect to the container.

The foregoing spout may be formed from separate pieces connected together in a suitable manner or may be formed as a unitary piece from metal or synthetic resinous materials.

The spout is extremely simple and may be readily affixed to a container by even the most unskilled person. To position the spout the flap 16 is pulled up in the usual manner by inserting a fingernail in the slot 17 and then grasping the end of the flap and thereafter raising it to the position shown in Figs. 3 and 4. The tab 21 being adhered to the flap 16 is simultaneously raised to the position as shown in Figs. 3 and 4 thus exposing the opening 18 in the inclined portion 13 of the container. The spout is then grasped between two fingers and the free end 31 of the resilient member 28 is disposed in the slot 17. Thereafter the resilient member is inserted between the liner 19 and the side member 11. The spout is pressed downwardly until the beveled edge 27 can be wedged under the bottom of the tab 21 when the tab is in its raised position, as shown in Fig. 4. Usually the tab 21 on being bent back tears loose from its connection with the liner 19 and the beveled edge 27 is thus forced or wedged between the liner 19 and the inclined portion 13 of the container. This is also the case when the tab 21 is omitted from the container construction. When the spout is in position the beveled edge 27 engages the tab 21 and the free end 31 is disposed between the liner 19 and the side member 11. With the spout so supported the resilient or spring member 28 is under stress and the spout is in effect wedged into position, since the resilient member tends to force the beveled edge 27 and the free end 31 into tight engagement with the respective parts of the container. Because the connection of the resilient member 28 with the pad 22 is on the side of the pad away from the bottom surface 23 the resilient member 28 also tends to force the bottom surface of the pad into tight engagement with the surface 24 adjacent the opening. This assures a liquid tight seal between the spout and the container. Thus, liquid in the container may be readily poured through the sleeve portion 26 as desired without leakage between the spout and the container.

Another embodiment of the invention is shown in Figs. 5 and 6. In this embodiment the liquid pouring device comprises a pad 31 with a beveled edge 32 and a liquid pouring sleeve portion 33 attached to the pad 31, constructed in a manner similar to that described for the embodiment shown in Figs. 1-4. In Figs. 5 and 6, however, a rigid wedge member 34 is attached to the pad 31 on the edge thereof away from the beveled edge 32. A rib 36 may be secured to the rigid member 34 and the pouring portion 33 to strengthen the spout structure. The angle between the pad 31 and the rigid member 34 in this instance is greater than the angle between the inclined portion 37 (see Fig. 6) and the side portion 38 of the container. The rigid member 34 is relatively wide at its free end so as to

be inserted between contiguous members, formed by a liner 41 and an external member 42 forming the side portion 38 on opposite sides of a recess on the side of the container shaped to receive the rounded end (such as shown in Fig. 3) of the flap 43 when the latter is in its closed position. The free end 44 of the rigid member 34 and the lateral edges thereof, where desired, may be beveled or the like to facilitate entrance thereof between the contiguous members.

To attach this spout to the container the liquid pouring portion 33 may be grasped between the thumb and finger and the free end 44 of the rigid member 34 is placed against the liner 41, exposed when the flap 43 is in the raised position shown in Fig. 6, and pushed downwardly until the end 44 thereof is inserted between the contiguous members 41 and 42 at opposite sides of the recess for the flap 43. The spout is pressed downwardly until the edge of the pad 31 adjacent the rigid member 34 engages the inclined portion 37 of the container. Thereafter the beveled edge 32 of the pad 31 is pressed downwardly until it engages the bottom of the flap 43 as shown in Fig. 6. Since the angle between the pad 31 and the rigid member 34 is greater than the angle between the side 38 and the inclined portion 37, the container, which inherently has some resiliency, is stressed when the beveled edge 32 engages the bottom of the flap 43 and the rigid member 34 is disposed between contiguous members 41 and 42 adjacent each side of the recess for the flap 43. As a result the pad 31 is forced into fluid tight engagement with the surface 46 adjacent the liquid opening 47 of the container. With the spout secured to the container in this manner liquid may be readily poured from the container as desired.

The foregoing constructions provide a detachable spout that is relatively inexpensive to manufacture, that is positive in its action so that there is no leakage between the spout and the container and that permits of accurately controlling the flow of liquid from the container, particularly small quantities such as is the case in pouring cream from a container into a cup of coffee.

I claim:

1. A detachable pouring device for a liquid container of the gable type having an opening disposed on one of the inclined portions forming the gable and a flap bendable outwardly to uncover the opening, comprising a pad having a flat bottom surface shaped to engage the surface of the container across the opening, a spout on said pad adapted for alignment with the opening, said pad having an abruptly beveled edge portion shaped to engage the bottom of the bendable flap when the latter is in its outward position to fixedly position said edge of the pad, and a wedge member connected to said pad on the side thereof away from the flat surface and in spaced relation thereto for wedging the flat surface against the container, said wedge member being inclined at an angle to the pad and having a portion adjacent the pad arranged to be in spaced relation to the side of the container and terminating in a thin end portion remote from the pad shaped to be inserted between contiguous members forming the side of the container, the angle between said wedge member and the pad being less than the included angle between an inclined portion of the gable and a side of the container to urge said beveled edge into engagement with the bottom of the flap and to urge said

flat surface of the pad into liquid tight engagement with the container when the spout is mounted in the above described position.

2. A detachable pouring device for a gable type liquid container formed from paper and having a flap defining a part of one of the inclined sides of the gable bendable outwardly from the plane of said side of the gable and a liner disposed in contiguous relation with portions of said inclined side of the gable and the side of the container beneath said flap and having an opening of substantially less area than said flap through which the contents of the container may be poured when the flap is in an outward position comprising a spout shaped to be in alignment with the opening, a pad having a flat surface shaped to engage the surface of the container adjacent the opening, said pad having a beveled edge portion terminating in a thin edge coplanar with said flat surface shaped to engage between the bottom of the bendable flap and the liner when the flap is in its outward position to force the flat surface into sealing engagement with the container, and a wedge member connected to said pad opposite said beveled edge and in outwardly spaced relation to said flat surface and terminating in a thin free end shaped to be inserted between the liner and the side of the container, said member extending at an angle with respect to said pad less than the included angle between the side of the container and said one inclined side of the gable, said member and said pad effecting deformation of said one inclined side of the gable and the side of the container to stress the container, when said spout is mounted as described, and urge the pad into tight engagement with the surface adjacent the opening.

3. A detachable pouring device for a gable type liquid container formed from paper and having a flap defining a part of one of the inclined sides of the gable bendable outwardly from the plane of said side of the gable and a liner disposed in contiguous relation with portions of said inclined side of the gable and the side of the container beneath said flap and having an opening of substantially less area than said flap through which the contents of the container may be poured when the flap is in an outward position, said pouring device having a flat lower face extending around the opening shaped to engage the container surface, a spout mounted on said pad to extend upwardly therefrom and communicating with the opening in the container for emptying the contents therefrom, said pad being formed with a peripheral edge portion beveled abruptly to define a surface tapering outwardly on the pad away from the spout and toward the flat lower face of the pad, said beveled edge portion on the pad being engageable against the bottom of the

bendable flap on the container when said flap is in its outward position to force the flat lower face of the pad tightly against the liner, and a wedge member connected to said pad diametrically opposite from said beveled edge in outwardly spaced relation to said flat lower face, said member extending downwardly from said pad to be angularly inclined with respect to the flat lower face thereof having a thin free end which forms the termination of said angularly inclined member positioned to be inserted between the liner and the side of the container to wedge the beveled edge of the pad against the bendable flap and to urge the flat face against the container.

4. A detachable pouring device for a gable type liquid container formed from paper and having a flap defining a part of one of the inclined sides of the gable, bendable outwardly from the plane of said side, and a liner disposed in contiguous relation with portions of said inclined side of the gable beneath the flap and having an opening of lesser area than said flap through which the contents of the container may be poured when the flap is lifted, said pouring device comprising a pad, a spout and a wedge member molded as a single piece from synthetic resin, said pad having a flat lower face adapted to seat over the opening in said liner, the spout extending outwardly from the upper face of said pad and communicating with the opening for emptying the contents of the container, said pad being formed with a peripheral edge portion beveled abruptly to define a surface tapering outwardly away from the spout and toward the flat face of the pad and a sharp edge coplanar with the bottom face, said beveled edge portion being engageable against the bottom of the bendable flap when the flap is in its outward position to force the flat lower face of the pad tightly against the liner, and a resilient wedge member connected to the pad diametrically opposite from the beveled edge in outwardly spaced relation to the flat lower face of the pad, said member extending downwardly at an angle with respect to said flat surface less than the included angle between the side of the container and the side of the gable, said member having a thin free end positioned to be inserted between the liner and the side of the container to wedge the beveled edge of the pad against the bendable flap and to urge the flat face against the liner.
